(57) **CLAIM**

The ornamental design for a butterfly-shaped medical patch as shown and described.

DESCRIPTION

FIG. 1 is a front perspective view of a butterfly-shaped medical patch of the present design.

FIG. 2 is a front view of the butterfly-shaped medical patch of FIG. 1.

FIG. 3 is a rear view of the butterfly-shaped medical patch of FIG. 1.

FIG. 4 is a right-side view of the butterfly-shaped medical patch of FIG. 1, wherein the left-side view of the butterfly-shaped medical patch is a mirror image of the right-side view.

FIG. 5 is a top view of the butterfly-shaped medical patch of FIG. 1; and,

FIG. 6 is a bottom view of the butterfly-shaped medical patch of FIG. 1.

The broken lines shown in the drawings illustrate portions of the butterfly-shaped medical patch that form no part of the claimed design.

1 Claim, 6 Drawing Sheets
